UNITED STATES PATENT OFFICE.

SOLOMON GREENHALGH, OF NEWARK, NEW JERSEY.

IMPROVEMENT IN STEAM-GENERATORS.

Specification forming part of Letters Patent No. 43,769, dated August 9, 1864.

To all whom it may concern:

Be it known that I, SOLOMON GREENHALGH, of Newark, in the county of Essex and State of New Jersey, have invented a new and Improved Steam-Boiler; and I do hereby declare that the following is a full, clear, and exact description thereof, which will enable others skilled in the art to make and use the same, reference being had to the accompanying drawings, making a part of this specification, in which—

Figure 1 represents a longitudinal vertical section of my invention; Fig. 2, a transverse vertical section of the same, the line *xx*, Fig. 1, indicating the plane of section.

Similar letters of reference indicate like parts.

This invention relates to certain improvements in that class of steam-boilers which are used to generate steam for heating purposes. In such boilers it is particularly desirable to obtain the steam as dry as possible, so that the same in passing through the heaters in the various parts of the building to be heated will deposit the smallest possible quantity of water.

The invention consists in the employment or use of one or more horizontal water-tubes, in combination with a series of vertical pipes forming the connection between the said water tube or tubes and one or more steam-chambers and suitable fire-flues, in such a manner that the horizontal and vertical water-tubes, and also the steam chambers, are exposed to the direct action of the fire from all sides, and the steam formed by the action of the fire on the water in the tubes has a considerable increase of temperature imparted to it before it is allowed to pass off to the heaters in the building to be heated.

A represent a series of horizontal tubes, made of sheet-iron or any other suitable material, and supported by the brick walls B, at a considerable distance above the grate C, as clearly shown in the drawings. These horizontal tubes connect with the water-supply pipe D, and each of them communicates, by means of a series of vertical tubes E, with a steam-chamber, F. The tubes E emanate from the tubes A, alternately on one and then on the opposite side, as clearly shown in Fig. 2 of the drawings, and they are made with an oval or elliptic cross-section, so that the body

of water contained therein is easily permeated by the heat of the fire coming in contact with the external surface of the tubes.

The steam-chambers F are constructed in the shape of inverted truncated pyramids, the cross-sections of which form trapezoids, as clearly shown in Fig. 2 of the drawings, or they may be constructed in any other suitable shape or form and of any suitable material. Each of these steam-chambers, with its vertical and horizontal water-tubes, forms a complete system for itself, and they are arranged side by side, so that their upper edges are in contact with each other and a continuous flat surface is obtained. The lower part of these steam-chambers is occupied by water up to a level with or somewhat above the upper gage-cock, a, in the water supply pipe D, and their upper part is occupied by the steam formed by the evaporation of the water in the tubes and chambers. The heat and products of combustion rise from the fire on the grate C, and they are compelled by the bridge-wall G and water-back H to pass up to the steam-chambers and over the top of the water-back. On following the flues b, formed by the inclined sides of the said steam-chambers, the products of combustion come in contact with the abutments C, which rise from vertical plates I into the flues b, and by these abutments and plates the heat is turned down and compelled to pass under the lower edge of the first steam-chamber and along the abutment d, which terminates at some distance from the front of said steam-chambers, so as to allow the heat to turn its front end and pass back along the second abutment, d', and finally forward again to the chimney-flue e. By means of the abutments d d' the heat is circulated several times over the steam-spaces of the chambers F, and the steam contained therein is partially superheated before it is allowed to pass off through the steam-pipe J. The flues on the upper surfaces of the steam-chambers are cleaned by means of hand-holes f in the rear wall, and a safety-valve of the ordinary construction is applied to prevent accidents from over pressure. Each of the steam-chambers with its water-tubes is made entirely independent of the others, and they are connected to the water and steam pipes by suitable union-joints, as clearly shown in Fig. 1 of the drawings. By this arrangement the operation of

putting up and taking down the boiler is considerably facilitated, and the capacity of the boiler can be increased to any desired extent simply by increasing the number of its sections.

The heating surface of my boiler is very extensive; it raises steam with a comparatively small expenditure of fuel, and it is of particular advantage for heating purposes, because the steam is partially superheated before it is allowed to leave the boiler.

Having thus described my invention, I

claim as new and desire to secure by Letters Patent—

The trapezoidal steam-chambers F, arranged in combination with the horizontal water-tubes A, vertical tubes E, water-backs H, plates I, and abutments c d d', in the manner and for the purpose substantially as herein shown and described.

SOLOMON GREENHALGH.
